HOLDER FOR MARKERS OR RAZOR BLADES

Isidore A. Chaikin, Great Neck, N. Y.

Application June 2, 1941, Serial No. 396,262

14 Claims. (Cl. 120—13)

My invention relates particularly to a holder for marking chalk used by tailors and dressmakers or for holding safety razor blades for ripping seams, as well as to provide a device for accomplishing the following purposes and objects:

A holder for a marker of wax-like material which prevents the marker from being bent and deformed by the heat and pressure of the hand of the user.

A holder which may use a greater part of the marker to reduce waste.

A holder which may also be used to sharpen the marker to make a better line.

A holder which holds the marker from slipping.

A holder which may also hold a safety razor blade in place of the marker.

A holder easily opened and applied to holding chalk or other things.

I accomplish these and other objects by the construction hereinafter described and shown in the accompanying drawing forming a part hereof in which:

Fig. 1 is a perspective view showing the application of my device.

Fig. 2 is a front elevation, the back being similar.

Fig. 3 is a front elevation of a modification.

Fig. 4 is a section at 4—4, Fig. 2.

Fig. 5 is a fragmentary detail in which a part of a safety razor blade has been added.

Fig. 6 is a section at 6—6, Fig. 5 and Fig. 2.

Fig. 7 is a perspective view of a typical marker or tailor's chalk and a part of my holder.

Similar reference characters refer to similar parts throughout the drawing and in the specifications to follow.

My holder is particularly adapted to hold the wax-like chalk most commonly used in marking fabrics, and which is ordinarily used by tailors, dressmakers, and for manufactured articles made of fabric. The chalk, a common term for this marker, is softened by the heat of the hand and soon becomes bent, twisted and otherwise deformed.

The surface of the marker is slippery and difficult to hold and by the use of my holder, the chalk is easily held and kept from softening. The marker may be sharpened and reversed so that both edges may be used until the marker is used up.

A safety razor blade may also be held in my holder and is firmly held while in use for ripping seams and for other purposes and is instantly removable.

Referring to the drawing, the construction of my holder may be followed. The side members 1 and 2 are preferably hinged to each other 3 along the edges 4 and 5 which are provided with

the hinge bosses 6 which are rolled over and around into cylindrical form to engage the hinge pin 7.

Preferably midway between the ends 8 and 9 of the side members 1 and 2 and projecting beyond the edges 4 and 5, I have provided the handle levers 10 and 11 which, when pressed toward each other open the side members, causing them to move apart or away from each other against the tension of the torsional spring 12 which is coiled around said hinge pin 7 and has its ends resting against the inner surfaces of the handle levers 10 and 11 which are preferably curved transversely, and the side marginal edges 13 are flanged inwardly to stiffen said handle levers and also prevent the ends of the torsional spring from becoming disengaged. The torsional spring operates the side members to close them and to hold them closed on the marker 14 or razor blade 15.

To permit the marker 14 to be nearly covered by said side members and to provide air spaces 14' between the marker and said members, each is curved transversely from the edges 4 and 5 to the edges 16 and 17 of the members 1 and 2.

The edges 16 and 17 are preferably sharpened to facilitate sharpening the marking edges 18 or 19 of the marker 14.

Positioned above the air spaces 14' and disposed for a substantial part along the outer surface of the side members 1 and 2, I have provided the knurled raised pads 20 and 21 which facilitate holding my holder between the thumb and finger and prevents slipping.

Between the pads and the edges 16 and 17 of the members 1 and 2, I have provided the inwardly depending toothed flanges 22 and 23 which are pressed inwardly from the metal of the side members thereby forming the slots 24.

The end teeth 25 are spaced longitudinally to engage the ends 26 of the slot 27 of the safety razor blade 15 and the toothed flanges 22 and 23 are spaced apart to suit the width of said slot 27, thus holding said razor blade in place between the side members 1 and 2 which clamp the razor blade firmly in place.

The intermediate teeth 28 are preferably openly spaced to engage and penetrate and grip the marker 14. The teeth and flanges thus are positioned to either engage the slot of a safety razor blade or the material of the marker, thereby holding either firmly in place between the side members 1 and 2 which clamp and secure them by means of the tension of the spring 12 and further by the pressure of the thumb and fingers on the pads 21 and 22.

In Fig. 3, I have shown a modification which is provided with side members *a* and *b* hinged *c* at the end *d*. The handle levers *f* project beyond the hinge *c* at the end. The slot *g* and

toothed depending flanges may be positioned at the center of the members and knurled pads *h* and *i* may be positioned at both sides of the slot *g*.

I have herein disclosed, in detail, a preferred construction embodying the underlying principles of my invention. To those skilled in the art to which this invention pertains, modifications may be apparent, and I do not wish to be limited to the details herein disclosed, which are to illustrate rather than to limit the scope of my invention, which is set forth in the appended claims.

I claim:

1. In a holder, a pair of hingeably secured side members having a sharpened edge opposite the hinge and a slot having toothed inwardly depending flanges positioned near to and parallel with said sharpened edges, and a pair of lever handles integral with said side members projecting beyond said hinges.

2. In a holder, a pair of hingeably secured side members having a sharpened edge opposite the hinge and a slot having toothed inwardly depending flanges positioned near to and parallel with said sharpened edges, and a pair of lever handles integral with said side members projecting beyond said hinges to open said side members when pressed.

3. In a holder, a pair of hingeably secured side members having a sharpened edge opposite the hinge and a slot having toothed inwardly depending flanges positioned near to and parallel with said sharpened edges, and a pair of lever handles integral with said side members projecting beyond said hinges, and a torsional spring having its ends bearing against the inner surfaces of said lever handles to close said side members.

4. In a holder, a pair of hingeably secured side members having a sharpened edge opposite the hinge and a slot having toothed inwardly depending flanges positioned near to and parallel with said sharpened edges, and a pair of lever handles integral with said side members projecting beyond said hinges, and knurled pads positioned between said slots and said hinges.

5. In a holder, a pair of hingeably secured side members having a sharpened edge opposite the hinge and a slot having toothed inwardly depending flanges positioned near to and parallel with said sharpened edges, and a pair of lever handles integral with said side members projecting beyond said hinges, and knurled pads positioned between said slots and said hinges facilitating a grip between the thumb and fingers, and spring means cooperating with the thumb and fingers in clamping a marker or razor blade between said side members.

6. In a holder, a pair of hingeably secured side members having a sharpened edge opposite the hinge and a slot having toothed inwardly depending flanges positioned near to and parallel with said sharpened edges, and a pair of lever handles integral with said side members projecting beyond said hinges, and knurled pads positioned between said slots and said hinges facilitating a grip between the thumb and fingers, and spring means cooperating with the thumb and fingers in clamping a marker or razor blade between said side members, said marker or razor blade being

released and removable by pressing said lever handles.

5 7. In a holder for a slotted razor blade or wax-like marker, a pair of hinged spring operated side members, each having a pair of toothed depending flanges to suit the slot in said razor blade or to engage and penetrate said marker.

10 8. In a holder for a slotted razor blade or wax-like marker, a pair of hinged spring operated side members, each having a pair of toothed depending flanges to suit the slot in said razor blade or to engage and penetrate said marker, said side members having a hinge and extending lever handles along one of their edges pressable to overcome said spring and to release said razor blades or said markers from said side members.

15 9. In a holder for a slotted razor blade or wax-like marker, a pair of hinged spring operated side members, each having a pair of toothed depending flanges to suit the slot in said razor blade or to engage and penetrate said marker, said side members being curved convexly on their outer surface to provide a space between said marker and their inner surface to reduce the heat from the thumb and fingers from softening said marker.

20 10. In a holder for a slotted razor blade or wax-like marker, a pair of hinged spring operated side members, each having a pair of toothed depending flanges to suit the slot in said razor blade or to engage and penetrate said marker, said side members being curved convexly on their outer surface to provide a space between said marker and their inner surface to reduce the heat from the thumb and fingers from softening said marker, and a knurled pad over said air spaces to prevent slipping.

25 11. In a holder for a slotted razor blade or wax-like marker, a pair of hinged spring operated side members, each having a pair of toothed depending flanges to suit the slot in said razor blade or to engage and penetrate said marker, and sharpened edges opposite said hinge for sharpening the edge of said marker.

30 12. In a holder for a slotted razor blade or wax-like marker, a pair of hinged spring operated side members, each having a pair of toothed depending flanges to suit the slot in said razor blade or to engage and penetrate said marker, and a hinge pin securing and passing through said spring.

35 13. In a holder for a slotted razor blade or wax-like marker, a pair of hinged spring operated side members, each having a pair of toothed depending flanges to suit the slot in said razor blade or to engage and penetrate said marker, and a hinge pin securing and passing through said spring, a pair of lever handles pressable to open said side members.

40 14. In a holder for a slotted razor blade or wax-like marker, a pair of hinged spring operated side members, each having a pair of toothed depending flanges to suit the slot in said razor blade or to engage and penetrate said marker, and a hinge pin securing and passing through said spring, a pair of lever handles pressable to open said side members, said lever handles having side flanges depending inwardly to receive and retain the ends of said spring.

ISIDORE A. CHAIKIN.
